DOCTOR BLADE MOUNTING

Lloyd Hornbostel, Beloit, Wis., assignor to Beloit
Iron Works, Beloit, Wis., a corporation of Wisconsin

Application April 27, 1945, Serial No. 590,709

5 Claims. (Cl. 92—74)

1

This invention relates to a doctor blade mounting, and more particularly to a doctor blade mounting for use in the making of paper or in the creping of paper or other web material.

It has heretofore been customary in the mounting of doctor blades to provide the doctor blade with end stub shafts which are journaled in bearings, and to secure weight arms to the stub shafts for holding the doctor blade against the roll, or cylinder, with the desired amount of pressure. It is difficult, if not impossible, with such prior art doctor blade mountings to adjust the pressure properly so as to cause the doctor blade to bear against the roll, or cylinder, with a uniform pressure throughout its length. Also, in the case of relatively long doctor blades for tending a wide roll, or cylinder, difficulty has been experienced due to flexing of the doctor blade under the torsion exerted at its ends, with the result that the bearing pressure between the doctor blade and the roll, or cylinder, varies at different points along the length of the doctor blade.

In accordance with the present invention, uniform pressures between the doctor blade and the roll, or cylinder, are maintained throughout the length of the doctor blade by the use of fluid-operated diaphragms in conjunction with reducing valves and pressure gauges for insuring that exactly the same pressure and the desired amount of pressure is exerted in holding the doctor blade against the roll, or cylinder. For this purpose, the two or more controlling diaphragms are operated from a common source of fluid under pressure, such as compressed air, and indicating gauges are associated with each of the diaphragms to enable the operator to control the pressures exerted by the fluid upon each of the diaphragms with great exactness.

Further, in the doctor blade mounting of my invention, the mounting itself is of rather massive construction while the doctor blade proper consists of a relatively thin, flexible metal blade. By virtue of the comparatively massive mounting for the doctor blade, very little distortion due to the torque applied to the ends of the shaft take place. Consequently, since the diaphragms serve to equalize the torque imparted to the ends of the doctor blade shaft, a uniform pressure along the length of the doctor blade proper is maintained between the edge of the doctor blade and the roll, or cylinder, against which the blade is pressed.

In addition to providing for uniform pressure between the doctor blade and roll, my doctor blade mounting construction includes means for

2

oscillating the doctor blade lengthwise of its axis. The purpose of this is to prevent the building up of dirt, or foreign material, at any one point between the doctor blade and the surface of the roll, or cylinder, and thus to prevent scoring of the roll surface or tearing of the paper web at such point. The doctor blade mounting thus includes bearings for the ends of the doctor blade shaft to permit such oscillatory movement and also includes hangers for the shaft bearings that compensate for any slight misalignment of the shaft.

It is therefore an important object of this invention to provide a mounting for a doctor blade that is of such construction as to insure the maintenance of uniformly equal pressures the length of the doctor blade between the doctor blade and the roll, or cylinder, against which the doctor blade is pressed.

It is a further important object of this invention to provide a doctor blade mounting that includes means for controlling and maintaining a uniform pressure of the optimum amount between the doctor blade and the roll, or cylinder, against which the blade is pressed, and that also includes means for oscillating the doctor blade lengthwise of its axis so as to reduce the tendency of the doctor blade to score the roll, or cylinder, or to tear the web of paper that is being doctored from the surface of the roll, or cylinder.

It is a further important object of this invention to provide a doctor blade mounting that includes fluid pressure operated diaphragms for effecting and maintaining a desired uniform pressure between the doctor blade proper and the roll, or cylinder, with which the blade cooperates in the removal of the web of paper from the roll, or in the creping and removal of the web, and that also includes manually operable means for independent operation of the doctor blade mounting in the event of an emergency.

Other and further important objects of this invention will be apparent from the disclosures in the specification and the accompanying drawings.

On the drawings:

Figure 1 is a broken side elevational view of a paper machine roll, or cylinder, with which is associated a doctor blade mounting embodying the principles of my invention.

Figure 2 is a broken side elevational view, similar to Figure 1, but taken from the other side of the machine.

Figure 3 is a broken, enlarged front elevational view, with parts broken away and in section.

Figure 4 is a broken elevational view, partly in section, of the mechanism for oscillating the doctor blade mounting, the connection with which is shown broken away at the righthand lower end of Figure 3.

Figure 5 is a view, partly in section, taken substantially along the line V—V of Figure 3, illustrating one of the diaphragm mechanisms.

Figure 6 is a sectional view, with parts in elevation, taken substantially along the line VI—VI of Figure 5.

Figure 7 is a view partly in section and partly diagrammatic of the fluid pressure piping system to the diaphragms.

As shown on the drawings:

In Figures 1, 2 and 3, the reference numeral 10 indicates a roll, or cylinder, such as the drying cylinder of a paper machine or of a creping machine such as is used for the creping of paper. Said roll 10 is suitably mounted for revolution in accordance with any of the conventional arrangements for mounting and revolving such rolls. Longitudinally extending I-beams 11 and 12 form a part of any such usual or conventional frame as may be employed for the mounting of the roll 10. Said I-beams 11 and 12 extend longitudinally of the machine on either side of the roll 10 and are supported in part by upright frame members 13, of which there are a number on either side of the machine.

The doctor blade mounting of my invention is indicated generally by the reference numeral 14. As illustrated, the doctor blade mounting 14 is supported from the I-beams 11 and 12 by means of brackets 15 and 16 that are of sufficient length to enable the doctor blade mounting to be properly positioned with reference to the roll, or cylinder, 10. As shown, the doctor blade mounting 14 is positioned in front of and well below the horizontal axis of the cylinder 10, but other positions of the doctor blade mounting are contemplated.

The doctor blade mounting 14 includes a shaft 17 which is, in general, parallel to the axis of the roll 10 and the ends of which are journaled in bearings indicated generally by the reference numerals 18 and 19. The bearings 18 and 19 are similarly mounted from the brackets 15 and 16, respectively, by means of plates 20 and 21. Since the two bearings 18 and 19 are identical, only the bearing 18 will be described.

Said bearing 18 comprises an open-ended cylindrical housing 22 on the top of which is formed an integral boss 23 that is internally threaded for receiving the lower end of a threaded hanger rod 24. Said hanger rod 24 extends freely through a guide ring 25 that may extend integrally from the plate 20 and that is formed with upper and lower segmental spherical surfaces 26 and 27 (Fig. 3). A collar nut 28 is threaded upon the hanger rod 24 below said guide ring 25 and is provided with a conformingly curved upper surface 29 for cooperation with the lower surface 27 of the guide ring. A second collar or nut 30 is threaded upon the upper end of the hanger rod 24 and is provided with a lower segmental spherical surface 31 for bearing against the upper guide ring surface 26. Each of said collars or nuts 28 and 30 is provided with wrench engageable holes 32 for turning the same to adjust the hanger rod 24 upwardly or downwardly. As will be apparent, the provision of the segmental spherical surfaces 26, 31 and 27, 29, together with the clearance between the hanger rod 24 and the guide ring 25, serves to permit

slight movement of the hanger rod 24 from the vertical. The construction described thus compensates for any slight misalignment of the shaft 17 from its position parallel to the axis of the roll 10.

The end of the shaft 17 that extends into the bearing housing 22 is reduced in diameter, as at 33, and is provided with a bearing sleeve 34 of such thickness as to compensate exactly for the reduction in diameter of said shaft. Said bearing sleeve 34 comprises the inner bearing race of a ball bearing assembly that includes balls 35, an outer bearing sleeve or race 36 and end collars 37. A separate sleeve 38, of the same thickness as the inner bearing sleeve 34, forms a continuation thereof on the outer extended end 39 of said shaft 17. The open ends of the housing 22 are closed by means of end seals 40 and 41 which are secured to said housing 22 by screws 42. The end seals 40 and 41 include suitable packing 43 for preventing loss of lubricant from the interior of said housing 22. The ball bearing assembly is retained within the housing 22 by means of split ring structure 44, between which and the housing 22 are provided segmental spherical surfaces 45 that render the split ring bearing block 44 self-adjusting.

As best shown in Figures 1 and 2, means are provided for adjusting each of the bearing assemblies 18 and 19 horizontally within the limits of movement made possible by the adjustability of the hanger rods 24 in the ring guides 25. Said means, which are in general similar in construction to the vertically arranged bearing hangers just described, include a horizontally disposed hanger rod 46, one end of which is inserted into a bifurcated member 47, the ends of which are swivelly mounted upon a pin 52 carried by a plate 48 that is secured to the lower end of one of the brackets 15 or 16 by means of bolts 49. Said hanger rod 46 extends freely through a ring guide 50 that is integrally formed with the bearing housing 22 and depends therefrom. On either side of the ring guide 50 is a nut or collar 51, which is internally threaded to receive said hanger rod 46 and that is provided on the side toward the guide ring 50 with a segmental spherical surface for mating with a corresponding segmental spherical surface on said guide ring 50. The swivel mounting of an end of each of the hanger rods 46 about a pin 52 permits the shortening or lengthening of the vertical hanger mountings that include the hanger rods 24.

While the ends of the shaft 17 are journaled in the bearings 18 and 19, such bearings are intended merely to permit a limited turning movement of the shaft 17 sufficient to swing the doctor blade assembly, indicated generally by the reference numeral 53 toward and away from the surface of the roll 10. This limited turning movement of the shaft 17 is normally accomplished through the medium of fluid operated diaphragm mechanisms, but in the case of emergency may also be independently operated manually. The diaphragm mechanisms will now be described.

As illustrated in Figure 3, there are two such diaphragm mechanisms, indicated generally by the reference numerals 54 and 55, one for each of the ends of the shaft 17. Since the two diaphragm mechanisms are identical in construction and operation, only that cooperating with the extended end 39 of the shaft 17 will be described.

The diaphragm mechanism 54 is suspended 75 from the under side of the I-beam 11 by means

of a strap 58 carrying at its lower end a pair of spaced plates 57 and 59 connected at their four corners by posts 60. As best shown in Figures 5 and 6, the lower plate 59 is in the form of a ring that is provided with lugs 59a for receiving the posts or bolts 60. A circular diaphragm 61 is clamped between the underside of the ring 59 and a bottom closure plate 62, bolted to said ring 59 by means of bolts 62a. Said bottom closure plate 62 is downwardly dished to provide a fluid pressure chamber 63 beneath said diaphragm 61. Piping 64 is connected to an opening 65 in said bottom closure plate 62 for the purpose of introducing a fluid under pressure into said chamber 63, as will later be described.

The free central portion of the diaphragm 61 is clamped between a circular lower plate 66 and a circular upper plate 67, the two plates being held together by means of bolts 68 that pass through the lower plate 66 and diaphragm 61 and are threaded into the upper plate 67. A strap 680 in the form of a closed loop encloses the diaphragm assembly and is supported from the diaphragm by a rectangularly shaped pad 69 that is secured to the upper surface of the upper plate 67 by means of bolts 70. The strap 680 is thus supported directly by the diaphragm 61 and is subject to the movements of said diaphragm in accordance with the amount of fluid pressure within the chamber 63.

The lower portion of said strap 680 is provided centrally with a cylindrical boss 71 into which is threaded the upper end of a hanger rod 72, a nut 73 serving to lock said upper hanger end against displacement from the boss 71. The lower end of said hanger rod 72 is threaded, as at 74 for free passage through a ring 75, above and below which are positioned nuts, or collars, 76 and 77, respectively, that are internally threaded for engagement with the threaded end 74. Said nuts, or collars, 76 and 77 thus provide for vertical adjustment of the ring 75 along the hanger rod 72, while the clearance between the ring 75 and the lower threaded end 74 permits of limited relative movement.

A pair of arms 78 extend outwardly and downwardly from the ring 75 to support at their lower ends a pair of cylindrical members 79 having aligned bores for receiving a pivot pin 80. A strap 81 has at its upper end an eye 82 (Fig. 1) that is pivotally mounted upon said pin 80 between the end members 79, 79. The lower end of said strap 81 is transversely bored to receive a pin 83 that extends through the spaced ears 84, 84 formed on a lever, indicated generally by the reference numeral 85. Said lever 85 is associated with a bell crank lever 86, which will now be described.

Said bell crank lever 86 is provided at one end with a cylindrical boss 87 that is keyed upon the extended end 39 of the shaft 17, as by means of a key 88. From said cylindrical hub portion 87 there extends an arm 89 that is bifurcated at its outer end to provide parallel spaced plates, 90, 90, which together constitute the other arm of the bell crank lever 86. A handle 91 is secured to the outer of the bifurcated end plates 90 in the lower corner formed by the junction of the external edges of said plates. Said handle 91 serves for manual manipulation of the bell crank lever 86. Both of the plates 90 are provided inwardly of the lower corner aforesaid with cylindrical bosses 92, 92 (Figs. 1 and 3) through which extends a pin 93. The lever arm 85 previously referred to is formed with a cylindrical boss 94 that is bored to receive said pin 93. The pin 93 is removable when it is

desired to move the doctor blade mounting manually. When, however, the doctor blade mounting is to be controlled or actuated through the medium of the diaphragms, the pin 93 is inserted in place and left in place so long as the diaphragms continue to function.

At the extreme upper ends of the plates 90, 90, the plates are bored to receive stationary pins 95, 95, which extend inwardly in spaced relation for receiving spaced cylindrical bosses 96, 96 formed on the upper end of the lever 85. Said bosses 96, 96 are integrally connected with another set of bosses 97, 97 that are at a lower level than the bosses 96 and that are bored to receive the pin 83 that passes through the lower end of the link 81. The pin 83 thus serves as the fulcrum pivot pin for the lever 85 when the removable pin 93 is removed. With the pin 93 removed, the pin 83 also serves as the pivot for the bell crank lever 86, so that by pulling forwardly on the handle 85a of lever 85 the operator can manually swing the doctor blade assembly 53 away from the roll 10. This is accomplished by moving the pin 95 about the pivot pin 83 as a center until the pin 95 is free to drop clear of the pin 83 (on the left hand side of the pin 83, as viewed in Fig. 1). The bell crank lever then swings downwardly and the doctor roll mounting swings away from the roll 10.

When however, the removable pin 93 is inserted in place to hold the lever arm 85 against movement, the link 81 and bell crank lever 86 function as a rigid unit and are subject to the action of the diaphragm in controlling the position of the doctor blade assembly 53 relative to the surface of the roll 10.

The doctor blade assembly 53 includes a pair of end sleeves 100, 100 that are adapted to be secured upon the shaft 17 for turning movement therewith. A doctor blade supporting member 101 is mounted upon said shaft 17 between said end sleeves 100, 100, to which said supporting member may be rigidly secured, or with which the supporting member may be integrally formed. The supporting member 101 comprises a massive bar of metal of generally rectangular cross section. An upstanding rib 102, which may be formed integrally with the body of the blade supporting member 101, is slotted along its upper edge to receive the doctor blade proper, indicated by the reference numeral 103. Said doctor blade proper 103 may be formed of relatively thin metal and is provided with an accurately ground working edge 104 adapted to bear against the surface of the roll 10 when in operation.

The mechanism for oscillating the doctor blade 53 will now be described. Said mechanism, as best shown in Figures 2 and 4, includes a motor 105 supported by a strap 106 from I-beams 11 and 12. The driving shaft 107 of said motor is connected to a coupling 108 with a driven shaft 109. Said driven shaft 109 is journaled at its free end in a bearing 110 also supported by a strap 111 from the I-beams 11 and 12. The driven shaft 109 carries an eccentric 112 upon which is mounted an eccentric strap 113. A crank arm 114 is secured to said eccentric strap 113 by means of a bifurcated end member 115. The ends of said bifurcated member 115 are secured to said eccentric strap 113 by means of pivot pins 116, 116, and said bifurcated end member is secured to one end of the crank arm 114 by means of a nut 117. The other end of said crank arm 114 is threaded, as at 118 for attachment to a bifurcated member 119, to which it is secured by means of a nut 120. The bifurcated member 119 carries at its free end a socket housing 121

having a segmental spherical inner wall 122 for receiving the ball end 123 of a rod 124. Said rod 124 may be integrally formed with or otherwise secured to the adjacent end 125 (Fig. 3) of the shaft 17. As will be obvious, when the motor 105 is driven, an oscillatory movement will be imparted to the shaft 17 through the eccentric and connections just described.

The operation of the diaphragm mechanisms will now be explained in conjunction with the diagrammatic showing in Figure 7. A fluid under pressure, such as compressed air, is connected to a main pipe 130, which has mounted in it a three-way valve 131. Said three-way valve 131 has one connection to an exhaust pipe 132 and another connection to a continuation of the pipe 130, indicated by the reference numeral 130a. By turning a handle 133 on said three-way valve 131, communication can be established through the valve between the pipes 130 and 130a, or between the pipe 130a and the exhaust pipe 132. The pipe 130a is connected by means of branch piping 134 to pipe lines 135 and 135a, in which are positioned check valves 136 and 136a, and also to pipe lines 137 and 137a, in which are positioned reducing valves 138 and 138a. Said pipe lines 135 and 137 are connected to a common pipe line 139 provided with a T 140. The pipe 64 leading from the pressure fluid chamber 63 within the diaphragm mechanism is connected to one branch of said T 140 and a pressure indicating gauge 141 is connected to the other branch of said T 140. Similarly, the pipe lines 135a and 137a are connected to a common pipe 139a, which is connected through a T 140a with the pipe 64a communicating with the pressure fluid chamber 63a of the diaphragm mechanism. A pressure gauge 141a is similarly connected to the T 140a.

With the doctor blade mounting assembled as illustrated in the drawings, the amount of pressure between the doctor blade edge 104 and the surface of the roll 10 is controlled through the diaphragm mechanisms by adjusting the pressure by means of the reducing valves 136 and 136a to the amount of pressure desired, as indicated on the pressure indicators 141 and 141a. The pressure can thus be regulated until it is exactly the same at both ends of the shaft 17. This pressure, as is obvious, is translated into a torque applied to the shaft 17 and from the shaft 17 through the sleeves 100, 100 and the associated blade mounting member 101 to the blade proper 103. As the fluid pressure within the diaphragm fluid pressure chambers 63 and 63a is increased, the diaphragms 61 are distended upwardly to elevate the straps 680 and through the hanger rods 72 and associated elements to elevate the pivot pins 83, and thus raise the free ends of the bell crank levers 86. Since the bell crank levers 86 are keyed through the hubs 87 to the ends 39 of the shaft 17, said shaft 17 has applied to it a torque tending to rotate the shaft in such a way as to move the doctor blade 103 toward the surface of the roll 10, or if already in contact with such surface to cause said doctor blade 103 to press more firmly against said roll surface.

During operation, the oscillating mechanism is set into movement by energizing the motor 105, causing the doctor blade 103 to oscillate in the direction of its length while being pressed against the surface of the roll 10. The amplitude of such oscillation is, of course, relatively slight, but should be sufficient to prevent scoring of the surface of the roll 10 and also prevent the accu-

mulation of dirt or foreign matter at any point between the doctor blade edge 104 and the roll surface.

In order to release the torque impressed upon the shaft 17 and doctor blade assembly 53 through the diaphragm mechanisms, it is only necessary to move the three-valve 131 to establish communication between the pipe line 130a and the exhaust pipe 132. With this setting of the valve, pressure is relieved from the fluid pressure chambers 63 and 63a through the check valves 136 and 136a and out through the exhaust pipe 132.

In addition to this means of relieving fluid pressure and thus rendering the diaphragm mechanisms inoperative, the operator may remove the pins 93 and manually operate the bell crank levers 86 by means of their handles 85a, using the handle 91 as an aid in this manual operation. By moving the handles 85a forwardly, the bell crank levers 86 may be swung slightly about the pivot pin 83 and to the back side thereof to permit the pivot pins 83 and associated parts to drop down. The shaft 17 is thereby rotated sufficiently to swing the doctor blade assembly 53 away from the surface of the roll 10.

The adjusting mechanisms already described, such as those for permitting horizontal and vertical adjustment of the shaft bearings 18 and 19, make possible a very nice adjustment of the doctor blade 103 relative to the surface of the roll 10 as well as a very delicate control of the pressures that are maintained between the doctor blade edge 104 and the roll surface.

In place of diaphragms, fluid pressure operated pistons may be employed.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A doctor blade mounting comprising a shaft, bearings for supporting said shaft for rotation, a doctor blade assembly fixedly secured to said shaft, fluid pressure actuated mechanisms, and means connecting one of said mechanisms to each end of said shaft, each of said means including a lever secured to a shaft end, a hanger operably connected to one of said mechanisms, a second lever pivotally connected to said first lever, and a member locking said first and second levers to form a unitary operative connection between said fluid pressure actuated mechanisms and said shaft for rotating said shaft.

2. A doctor blade mounting comprising a rotatable shaft, a doctor blade assembly fixedly secured to said shaft, and including a doctor blade rotatable with said shaft into and out of pressure contact with a roll, fluid pressure actuated mechanisms, hangers operatively connected to said mechanisms, first levers secured to said shaft, second levers pivotally connected to said first levers, and removable means locking said first and second levers together to provide a rigid unitary connection between said mechanisms and said shaft, whereby said fluid pressure actuated mechanisms can be operated to hold said doctor in pressure contact with the roll, said second levers being manually operable upon removal of said locking means to effect relative movement between said hangers and said first levers and cause said shaft to rotate said doctor blade out of pressure engagement with the roll.

3. A doctor blade mounting comprising a shaft, bearings for the ends of said shaft, a doctor blade assembly fixedly secured to said shaft, a doctor blade forming a part of said assembly, means adjustably supporting said bearings to align said shaft with respect to a roll to be doctored, fluid, pressure actuated mechanisms, hangers of adjustable length depending from said mechanisms, first levers fixedly secured to said shaft to rotate the same, second levers pivotally connected to said first levers, of adjustable effective length straps pivotally connected said second levers to said hangers, and removable means locking said first and second levers to provide a rigid unitary connection between said mechanisms and said shaft to hold said doctor blade in pressure contact with the roll, said second levers being operable upon removal of said locking means to increase the effective lengths of said straps to cause rotation of said shaft and movement of said doctor blade away from said roll.

4. A doctor blade mounting comprising a shaft, a doctor blade assembly fixedly secured to said shaft, bearings for rotatably supporting said shaft, fluid pressure actuated mechanisms, a strap connected to each of said mechanisms, a cylindrical boss on the lower portion of said strap, a hanger rod having threaded ends locked at its upper end to said boss, a ring threaded onto the lower end of said hanger and vertically threadably adjustable thereon, a pair of arms extending outwardly and downwardly from said ring, a pair of cylindrical members having aligned bores at the lower ends of said arms, a second strap pivotally carried by said cylindrical members, a first lever pivotally connected to said second strap, a second lever pivotally connected to said first lever and to said shaft, and a member

locking said first and second levers to form a unitary operative connection between said fluid pressure actuated mechanisms and said shaft for rotating said shaft, the position of said doctor blade being adjustable by adjusting said ring vertically thereby rotating said shaft.

5. In the combination of a doctor blade mounting with a roll against which the doctor blade is to be pressed, a shaft, bearings for supporting said shaft for rotation, a doctor blade assembly fixedly secured to said shaft, fluid pressure actuated mechanisms, means connecting one of said mechanisms to each end of said shaft, each of said means including a hanger operably connected to one of said mechanisms, a threadably adjustable member in engagement with said hanger for biasing said shaft for controlling pressure of said doctor blade against said roll, and levers for unitary operative connection from said adjustable member to said shaft for rotation of said shaft, one of said levers being releasable for manual operation of said shaft and doctor blade assembly.
